Primary Examiner — Paula Allen Greene(74) *Attorney, Agent, or Firm* — Whitham, Curtis & Cook(57) **CLAIM**

We claim the ornamental design for a headphone, as shown and described.

DESCRIPTION

FIG. 1 is a perspective view of a headphone;
 FIG. 2 is a front elevational view of the headphone;
 FIG. 3 is a rear elevational view of the headphone;
 FIG. 4 is a top plan view of the headphone;
 FIG. 5 is a bottom plan view of the headphone;
 FIG. 6 is a left side elevational view of the headphone;
 FIG. 7 is a right side elevational view of the headphone;
 FIG. 8 is a right side perspective view of the headphone of FIG. 2 as seen from arrow 8 of FIG. 2; and,
 FIG. 9 is an enlarged partial end view of the headphone taken along line 9-9 of FIG. 8.
 Portions of the drawings shown in broken lines form no part of the claimed design.
